(21) Appl. No.: **29/122,335**

(57) **CLAIM**

(22) Filed: **Apr. 25, 2000**

The original design for a convexly curved grip of camera, as shown and described.

(51) LOC (7) Cl. **16-05**

DESCRIPTION

(52) U.S. Cl. **D16/243**

(58) Field of Search D16/200-206,
D16/217, 218, 237, 243; 396/176, 177,
535-541, 544

FIG. 1 is a front elevational view of a convexly curved grip of camera showing our new design;
FIG. 2 is a back elevational view thereof;
FIG. 3 is a top plan view thereof;
FIG. 4 is a bottom elevational view thereof;
FIG. 5 is a right side elevational view thereof;
FIG. 6 is a left plan view thereof;
FIG. 7 is front perspective view thereof; and,
FIG. 8 is a back perspective view thereof.
The broken lines in all drawing views are for illustrative purposes only, represent environment, and form no part of the claimed design.
